J. S. TARR.
BUTTON DRILLING MACHINE.

No. 593,061.

Patented Nov. 2, 1897.

UNITED STATES PATENT OFFICE.

JOSEPH S. TARR, OF CLEVELAND, OHIO, ASSIGNOR TO WILLIAM S. CLARK,
OF ERIE, PENNSYLVANIA.

BUTTON-DRILLING MACHINE.

SPECIFICATION forming part of Letters Patent No. 593,061, dated November 2, 1897.

Application filed February 11, 1897. Serial No. 623,006. (No model.)

To all whom it may concern:

Be it known that I, JOSEPH S. TARR, a citizen of the United States, residing at Cleveland, in the county of Cuyahoga and State of Ohio, have invented certain new and useful Improvements in Button-Drilling Machines; and I do hereby declare the following to be a full, clear, and exact description of the invention, such as will enable others skilled in the art to which it appertains to make and use the same.

The invention relates to a machine for automatically drilling a plurality of holes in buttons. The machine includes a plurality of chucks for holding the button-blanks, preferably one more chuck than the number of holes to be drilled in each button-blank, a plurality of rotating drills, one for each hole to be drilled, mechanism for presenting the button-blanks successively to the action of the different drills, and mechanism for successively discharging the finished buttons from the chucks and for inserting button-blanks into the empty chucks.

In the drawings, Figure 1 is a plan view of the machine. Fig. 2 is a front elevation thereof. Fig. 3 is a sectional side view on line 3 3 of Fig. 1. Fig. 4 is a sectional side elevation on line 4 4 of Fig. 1. Fig. 5 is an enlarged sectional view of one-half of the machine on line 5 5 of Fig. 3, and Fig. 6 is an enlarged longitudinal section of the mechanism for feeding the buttons to the chucks.

Referring to the parts by letters, A represents the bed of the machine, at the ends of which are the two standards *a a*, in which the operating-shaft B is journaled, and the two standards *a' a'*, which support a non-rotatable cylindrical shaft C. This shaft C is a convenient practical means for supporting the various fixed and rotating parts, as hereinafter described, but it is not my intention to limit my invention to this particular means for supporting such parts.

D D' represent two immovable plates which are secured upon this shaft C. These two plates support the adjustable bearings *g* of the four longitudinally-movable drill-shafts G, which drill-shafts are parallel to each other and to the shaft C, and these plates also support the sliding plunger V, which forms

part of the mechanism for automatically feeding the buttons to the chucks, which I will presently describe. These drill-shafts and plunger are approximately the same distance from each other and from the axis of shaft C. 55

The bearings *g* for the drill-shafts are rectangular boxes set into holes *d* in the plates D D', and these boxes are moved to right or left or down by means of set-screws *g' g' g'*, 60 which set-screws also hold the boxes at the desired distance from the axis of the shaft C. The holes should be drilled in the button-blanks at points equidistant from each other and at equal distance from the center of the 65 button-blank. These bearing-boxes are therefore adjusted up or down or to right or left to bring the axes of the drill-shafts in line with proper point on the button-blank in the chucks adjacent to said shafts. On each drill-shaft is secured an operating-pulley *g'4*, and each drill-shaft is surrounded by an expandable coil-spring *g'7*, the ends of which bear against the bearings of the shaft in the plate D and against the hub of this pulley. In the 75 ends of the drill-shafts are chucks for securing the drills therein.

J represents a plate which is mounted upon the shaft C, upon which it is adapted to slide, but is prevented from turning by a spline. 80 Bolts *j* screw into this plate at points where their heads will engage with the rear rounded ends of the drill-shafts. It is obvious that when this plate is caused to slide upon shaft C to the left, as shown in the drawings, these 85 various bolt-heads will force the drill-shafts to the left in their bearings and that when this plate is retracted or moved to the right the springs surrounding the drill-shafts will move them to the right. 90

Loosely mounted on the shaft B is a pulley K, driven by a belt *k* from a counter-shaft, and a belt *k'*, which passes around said pulley, likewise passes in a sinuous path around the four pulleys *g'4*, which are attached to the 95 drill-shafts, wherefore all of the drill-shafts are simultaneously revolved, although two of them are revolved in one direction and two in the other. This makes no difference, because the drills which are used to drill the 100 holes in the buttons will operate equally well when rotated in either direction. The plate

J is caused to slide upon the shaft C by means of a fork-lever H, adjustably pivoted to the post a², which rises from the bed-plate. Its front end bears against the right face of the plate J. The rear end of this lever carries a friction-roller h, which bears against the face of a disk M, having on its face a cam m, which disk is secured to the shaft B. The shaft B is rotated by means of the pulley b, which is driven from a counter-shaft.

N represents a rotating disk which is mounted upon the shaft C, being prevented from moving along said shaft by the collar c and the hub r', which is fixed to the shaft.

15 On the side thereof which faces the drills are five chucks, arranged at regular intervals. This disk is rotated one-fifth of an entire revolution every time the shaft B revolves once by means of the notches n in the edge 20 of said disk, the pawl P, which is adapted to engage in said notches, and the crank on the shaft B, to the crank-pin of which the rear end of this pawl is pivoted.

The button-holding chucks consist each of 25 an adjustably-fixed plate n', having a right-angled notch in its inner end, which plates are secured to the face of the disk N by screws n⁵, which pass through slots n⁶ in said plates, and the radially-movable correlative 30 plate n², having a right-angled notch in its outer end. The button is held between the two plates and in these notches. The plate n² is movably secured to the disk by screws n⁷, passing through slots n⁸, and it is moved 35 radially outward by means of a coil-spring n⁴, which surrounds a shank n³ on its inner end. It is moved inward to release the button from the embrace of the chuck by means of a cam-shaped flange R, which engages with a friction-wheel n⁹, mounted upon a pin n¹¹, which projects from the plate n². This flange R is secured to the arm r, which projects outward 40 from the hub r', which is fixed to the shaft C.

The means for automatically feeding the 45 buttons into the chucks consist of a sleeve T, which is longitudinally movable through a hole in the plate D and through another hole in the boss r² on the outer end of the arm r. The diameter of the hole in this sleeve is a 50 trifle larger than the diameter of the buttons. A flat tube S is secured upon the end of this sleeve. It stands in a nearly vertical position, and it is in open communication with the interior of the sleeve, wherefore when 55 buttons are placed in this tube they will fall by gravity into the sleeve. A plunger V is longitudinally movable in the sleeve T, in which it fits, and in a suitable bearing in the plate D, and its right-hand end passes through 60 the plate J, and a coil-spring V' surrounds this plunger and thrusts endwise against a nut v' thereon and against the plate J, acting, therefore, to move the plunger to the left whenever the plate J so moves as to permit such action. A pin v², which is connected 65 with the plunger, passes through a longitudinal slot t² in the sleeve T. A coil-spring t'

surrounds the left end of the sleeve and thrusts against the boss r² and against the flange t upon said sleeve, wherefore the sleeve 70 is moved toward disk N whenever it can so move. Under normal conditions the right end of the slot t² engages with the pin v², which prevents for the time being any movement in that direction.

75 The parts described operate in the following manner and sequence: Assume that a button is in the embrace of each of the chucks carried by disk N and that the drill-shafts

80 have just been retracted after the drills have drilled holes in the buttons. The shaft B is

constantly revolved, and it now operates the pawl P and causes the disk N to be turned one-fifth of a revolution. Fig. 3 shows these parts when the disk N is about midway between two stopping-points. When the disk

85 N reaches the position in which it should stop, a tooth w on the spring W engages with a notch n⁸ in the periphery of said disk. Before the disk reaches this point one of the

friction-rollers n⁹, which is mounted upon a pin projecting to the right from the plate n², engages beneath the cam-flange R. This

90 causes the particular plate n² which carries said roller to be drawn radially inward in opposition to its spring, the result being that the button which had been held between the two plates n' n² is permitted to drop out.

This happens, as before stated, before the disk N reaches the position where it will stop. When it does stop, the opening between the plates n' n² of the now empty chuck is in

95 line with the plunger V, as shown in Fig. 5. The buttons in the embrace of the other chucks are in line with the various drills. The continued revolution of shaft B causes

100 the cam m of disk M to engage with the friction-roller h on the lever H, which causes said lever to rock upon its pivot, with the result of forcing the disk J to the left, whereby the

105 four drill-stems are moved so as to cause their drills to drill holes in the several buttons. At the same time the plunger V is

110 moved to the left by its spring V'. As it so moves it permits the spring t' to move the sleeve T to the left until its end strikes the plates n' n². A further movement of the

115 plunger V which follows pushes the button in the sleeve out against the disk N and between the two jaws n' n², thereby pushing the spring Z out. The cam M passes out of

120 engagement with the friction-roller n⁹, whereupon the springs surrounding the drill-stems move said drill-stems, and consequently the disk J, to the right. Just after this move-

125 ment has begun and before it is quite completed the pawl P again begins to move the disk N. Almost immediately after this move-

130 ment begins the roller n⁹ passes out of engagement with the flange R, whereupon the

135 spring n⁴ moves the jaw n² forward, and the button is grasped between the two jaws n' n²,

140 having been held in position between them until it was so grasped by the end of the

sleeve T. The further backward movement of the plunger V brings the pin v^2 into engagement with the end of the slot t^2 , whereby the sleeve T is retracted.

- 5 The movements above described are repeated indefinitely, the result being that each button is successively presented to the action of each of the four drills and is finally automatically released from the clutching-jaws.
- 10 It will be noticed also that all four drills act simultaneously, each upon a different button, and that when they are drilling holes into the buttons a button-blank is being automatically inserted in the then empty chuck.
- 15 The four drills are offset a very little and in different directions from the center of the button, wherefore the drills act upon four points equidistant from the center of the button and at equal intervals apart. It will
- 20 also be noticed that the sleeve T is moved against plates n^1 n^2 and the button-blank is fed into the empty chuck by the action of springs, whereby the blanks, whatever be their thickness, are firmly pressed against
- 25 the disk N and between the plates n^1 n^2 without danger of breaking any of the co-operating parts.

- The bolts j afford means for changing the normal position of the drill-shafts to compensate for the wearing away of the drills. The adjustable fulcrum of the lever H, which may be secured at any point in the slot a^4 , furnishes means whereby the throw of the drill-shafts may be varied as desired.
- 35 To insure the discharge of the button from the chucks as they are opened, I secure upon the back of disk N five bent springs Z, whose ends project through holes n^{12} in the disk between the plates n^1 n^2 and bear with a continuous, but light pressure upon the buttons between said plates.

By adjusting the plates n^1 out or in the chucks are adapted to hold buttons of different sizes.

- 45 Having described my invention, I claim—
1. In a button-drilling machine, in combination, a rotatable chuck-carrying disk, mechanism for moving the same intermittently, a series of self-closing chucks supported at regular intervals on one face of said disk, mechanism for opening said chucks sequentially, a series of longitudinally-movable drill-shafts, springs for moving said shafts independently away from the work, a button-feeding device
- 50 consisting of a sleeve which is parallel with the drills and in line with the open chuck, and has an opening for the introduction of button-blanks, means for moving the same toward and from said chuck, a plunger movable in said sleeve, a spring for moving it toward the disk, a plate J for simultaneously governing the movements of the drill-shafts, feed-sleeve and plunger toward and from the disks, and means for moving said plate, substantially as and for the purpose specified.

- 60 2. In a button-drilling machine, in combination, a plurality of longitudinally-movable

drill-shafts, means for holding button-blanks in line therewith, springs for independently moving said shafts from the work, a movable plate which simultaneously moves all of said drill-shafts toward the work, adjustable bolts carried by said plate and engaging with the ends of the drill-shaft, a lever for moving said plate, an adjustable fulcrum for said lever, and a cam for operating said lever, substantially as and for the purpose specified.

3. In a button-drilling device, in combination, the disk N carrying on one face a plurality of equally-spaced self-closing chucks, mechanism for moving said disk intermittently, a plurality of longitudinally-movable drill-shafts, springs for independently moving said shafts from the work, means for sequentially opening the chucks, a longitudinally-movable sleeve T, a vertical tube S which discharges button-blanks singly into the sleeve T, a plunger in sleeve T, the plate J, through which the rear end of the plunger passes, a nut on said end, a spring V, the adjustable bolts j , a shaft B, and mechanism operated by said shaft for moving disk N and plate J, substantially as and for the purpose specified.

4. In a button-drilling machine, the combination of a plurality of button-holding chucks, and mechanism for sequentially opening them and presenting the open chuck to the button-feeding mechanism, with button-feeding mechanism consisting of a longitudinally-movable sleeve, an approximately vertical tube secured upon and discharging into said sleeve, a plunger in the sleeve and mechanism for moving the sleeve and plunger toward the open chuck to guide the button in the sleeve and force it into the open chuck and then withdraw said sleeve and plunger, substantially as and for the purpose specified.

5. In a button-drilling machine, the combination of a plurality of button-holding chucks, and mechanism for sequentially opening them and presenting the open chuck to the button-feeding mechanism, with button-feeding mechanism consisting of a longitudinally-movable sleeve, an approximately vertical tube secured upon and communicating with the interior of said sleeve, a plunger in the sleeve, a spring exerting its force to move the sleeve toward the open chuck, a pin on the plunger projecting into a longitudinal slot in the sleeve, a spring exerting its force to move the plunger forward, and means for retracting said plunger, substantially as and for the purpose specified.

6. In a button-drilling machine, in combination, a rotatable disk carrying a plurality of button-holding chucks each consisting of a fixed jaw, a movable jaw, a spring for closing said movable jaw, and a projection n^{11} on said jaw, and the friction-roller n^9 , a plurality of longitudinally-movable drill-shafts, their operating mechanism, a longitudinally-movable button-feeding sleeve, an arm r in which said sleeve is supported, a cam-flange R on

said arm for engaging with the friction-roller *n*^o, a spring for moving the sleeve toward the open chuck, a spring-actuated plunger for forcing a button from the sleeve into said open chuck, and means for retracting said sleeve and plunger, substantially as and for the purpose specified.

7. In a button-drilling machine, the combination of an intermittently-moving rotating disk, a plurality of button-holding chucks carried thereby, a plurality of longitudinally-movable drill-shafts and their operating mechanism, a pair of bearing-boxes *g* in which each of said drill-shafts is mounted, said boxes being capable of adjustment in four directions transversely of the drill-shafts, whereby said shafts may be moved transversely in any direction, and means for locking said boxes in place, substantially as and for the purpose specified.

8. In a button-drilling machine, the combination of an intermittently-moving rotating disk, a plurality of button-holding chucks carried thereby, a plurality of longitudinally-movable drill-shafts and their operating mechanism, the plates *D* and *D'* having holes *d* through them by which they surround said drill-shafts, bearing-boxes *g* within said holes and embracing said drill-shafts and set-screws projecting through said plates into said holes *d* and engaging with said bearing-boxes, whereby said bearing-boxes may be adjusted in any transverse direction, substantially as and for the purpose specified.

In testimony whereof I affix my signature in presence of two witnesses.

JOSEPH S. TARR.
